UNITED STATES PATENT OFFICE.

WILLIAM H. C. HIGGINS, JR., OF LAPORTE, INDIANA, ASSIGNOR TO M. RUMELY COMPANY, OF LAPORTE, INDIANA, A CORPORATION OF INDIANA.

PLOW-LIFT.

1,112,796.

Specification of Letters Patent.

Patented Oct. 6, 1914.

Application filed December 15, 1913. Serial No. 806,663.

To all whom it may concern:

Be it known that I, WILLIAM H. C. HIGGINS, Jr., a citizen of the United States, residing at Laporte, in the county of Laporte and State of Indiana, have invented a certain new and useful Improvement in Plow-Lifts, of which the following is a specification.

My invention relates to improvements in gang plows, particularly with regard to the mechanism for lifting and lowering them into the ground.

It is illustrated somewhat diagrammatically in one of its forms in the accompanying drawings, wherein—

Figure 1 is a plan view of a portion of a gang plow device containing my improvements; Fig. 2 is an end elevation with parts broken away looking toward a portion of the device shown in Fig. 1 as indicated by the arrow 2; Fig. 3 is a section on the line 3—3 of Fig. 1 with the parts in the same position as they are shown in Fig. 2, that is, with the plows out of the ground; Fig. 4 is a similar cross section with the parts arranged to permit a plow to enter the ground; Fig. 5 is a similar cross section with the parts in the position which they assume when the plows are in the ground; Fig. 6 is a similar cross section with the parts in the position which they assume when a plow is lifted.

Like parts are indicated by the same letter in all the figures.

A is a transverse frame piece associated in any desired manner with the longitudinal frame piece A¹ mounted on the axle A² which turns with the driving wheel A³ and carries the sprocket wheel A⁴, which by means of a chain A¹⁰ imparts motion to the sprocket wheel A⁵ on the shaft A⁶ rectangular in cross section. It will be understood, of course, that the frame is extended in both directions, that there is another wheel A⁸ at the other end of the shaft A² and that the plows are dragged and controlled by a suitable mechanism in the rear of the parts here shown. Such additional parts are set forth in my copending application 786,211, filed August 23, 1913, and since they form no part of the invention here under consideration, I have not deemed it necessary to illustrate them more fully,

and, indeed, any form of structure relating to the plow beams and the particular rear supporting wheels, chain and other parts for raising and lowering them could be employed in connection with what is the subject matter of this invention. The frame here illustrated is supposed to be a portion of the frame associated with five plows, and the part which is illustrated is the driving mechanism for all the plows and the controlling mechanism for one of them is placed in front of the middle plow.

The sprocket wheel A⁴ forms part of or contains within itself a clutch mechanism which is not here illustrated, because it forms part of the subject matter of the prior application herein above referred to. This clutch mechanism contains a locking wheel B, a roller B¹ on an arm B² from which leads a rope B³. By pulling the rope the roller is withdrawn from an aperture in the wheel B and the clutch is permitted to operate so as to cause the shaft A⁶ to make one complete revolution. If the rope B³ has been previously slackened, the clutch will operate to throw the shaft A⁶ out of gear after it has completed one revolution. In other words, the mechanism at this point not fully shown may be any clutch which tends to connect the moving part with the shaft, and particularly any clutch which makes such connection and then disengages the part when the shaft A⁶ has made one revolution.

C is a gear wheel on the shaft A⁶ meshing with the gear wheel C¹ on the short shaft C². Attached to this shaft and gear wheel C², C¹ is the cam C³.

C⁴ is a downwardly open V-shaped device having at its lower extremities the rollers C⁵, C⁶. It is rigidly mounted on the shaft C⁷ and the finger C⁸ is also rigidly connected to the shaft C⁷ and is perforated at C⁹ to permit the free passage of the rod C¹⁰. This rod is pivoted at C¹¹ to one end of the short lever C¹², which is itself pivoted at C¹³ to the lower end of the link C¹⁴ and is provided with a latch end C¹⁵ to engage a block C¹⁶ held by the bolt C¹⁷ on the frame piece A. The link C¹⁴ is totally mounted on the shaft C⁷. The cam C³ when it rotates from the position shown in Fig. 3 to that shown in Fig. 4,

rocks the V-shaped part to its new position, thus depressing the finger C^8 . A spiral spring C^{18} encircling the rod C^{10} , is securely attached at one end to the pivot pin C^{11} and at the other to a pin C^{19} on the finger C^8 . From this it appears that depressing the finger C^8 compresses the spring C^{18} and causes it to tend to rock the lever C^{12} on its pivot, or, in other words, to bring it into the position shown in Fig. 4. The action of this spring, however, is not strong enough to rock the lever C^{12} until its latched end C^{15} is loosened or freed from contact under pressure with the block C^{16} .

Putting the spring C^{18} under pressure is the first result of rotating the shaft in the direction of the indicated arrow. The next thing which it does is to bring the cam D which is mounted on the shaft A^6 against a roller D^1 on the link C^{14} , thus tending to force the link at its lower end toward the left, which is indicated in Fig. 4 by the gap between the frame piece E and the lower end of the link C^{14} as compared with the re-

lation of these parts as indicated in Fig. 3. The cam D in contact with the roller D^1 is illustrated in dotted lines in Fig. 4. The shaft A^6 is now moved one quarter of its revolution and the particular cam D under consideration, in coöperation with the cam C^3 , has brought the parts into the position indicated in Fig. 4, where the spring C^{18} is under compression, the lever C^{12} has been rocked on its pivot and released from the block C^{16} .

F is a rod pivoted at C^{13} to the lower end of the link C^{14} and carried backward to a point where it is connected to a mechanism for lifting the particular plow in question.

The plows being out of the ground, when the parts are in the position as indicated in Fig. 3, the particular plow attached to the rod F is being held out of the ground by reason of the engagement of the end C^{15} of the lever C^{12} with the head C^{16} , but when the parts are forced into the position indicated in Fig. 4, the spring C^{18} being under compression raises the end C^{15} of the lever which has been first retracted so that the plow is ready to be lowered into the ground, and this is accomplished by the further rotation of the shaft A^6 which brings the cam D back to its original position as shown in Figs. 3 and 5. This, however, has resulted, the moment the cam D is freed from the roller D^1 , which is immediately after the parts have passed from the position shown in Fig. 4, in permitting the link to swing backwardly into the position indicated in Fig. 5, which carries the rod F rearwardly, thus permitting the plow in question to drop into the ground.

The mechanism containing the gears C_1 , the V-shaped piece C^4 , the cam C^3 and their associated parts is not duplicated, for

its purpose is, by turning the shaft C^7 which extends across the machine, to put the pressure on each of the fingers C^8 , there being one for each plow, and thus to compress each of the springs C^{18} .

With each plow there is associated a cam D , but these cams are staggered so as to successively operate, and with each plow is associated the double link C^{14} , and assuming that all of the springs C^{18} have been put under pressure or compressed, all of the levers C^{12} will tend to assume the position indicated in Fig. 4. As each of the cams D comes around to position, it will swing forward the double link C^{14} associated with it, draw back the plow rod F and with it the lever C^{12} , and permit the latter to be thrown into the position shown in Fig. 4 by the pressure of the spring C^{18} . Some portion of the mechanism associated with the plows when the part F is in the position shown in Fig. 5, comes to rest upon the frame and the plow is dragged forward in the usual manner. The shaft A^6 has made a complete revolution, but the gear C^1 has made a half revolution, and therefore the cam C^3 is now turned downwardly instead of upwardly as indicated in Fig. 3. If now the operator desires to raise the plows from the ground, he has only to pull on the rope B^3 , whereupon the shaft A^6 will be coupled to the sprocket wheel A^5 so as to be made to make one complete revolution as before.

The first action by reason of the engagement of the cam C^3 with the roller D^1 on one leg of the V-shaped piece is to swing the V-shaped piece to the left on the shaft C^7 , to lift upwardly all the fingers C^8 and thus put a tension on all of the springs C^{18} and so throw all of the levers C^{12} downwardly. This rotational action of the shaft A^6 causes the cam D to descend, as indicated in Fig. 6, and to throw the double link C^{14} to the left. This permits all of the parts to come into the position shown in Fig. 6, because the tension on the spring C^{18} tends to throw the end C^{15} of the lever C^{12} down upon the frame and back of the block C^{16} . The plow is lifted out of the ground by the retreat toward the left of the lower end of the link C^{14} , and when a further motion of the shaft A^6 from the position shown in Fig. 6 disengages the cam D from the roller D^1 , the link C^{14} will move slightly toward the right and bring the parts again to the position shown in Fig. 3, where the plows are locked out of the ground. As each of the staggered cams D reaches its respective roller D^1 , the same action will take place and at the end of the cycle all of the plows will be locked in position out of the ground. Thus it is possible by positioning and proportioning and setting the parts, to successively raise or lower all of the plows so as to successively take them out of or let them drop into the ground.

ground in such manner that they will begin to plow or discontinue plowing a line at substantially right angles to the line of travel of the machine.

5 The use and operation of my invention has already been perhaps sufficiently described.

An apparatus constructed as here shown so as to make a complete machine with any 10 desired number of plows is intended to be attached to the rear end of a tractor and to drag the plows in the proper relation one behind the other. The operator on the tractor platform has only to draw upon the 15 line B³ whenever he desires either to raise or lower the plows. He draws upon the line, thus throwing the clutch into action, whereupon he immediately releases the line and the operation continues until the square 20 shaft has made one complete revolution and the gear wheel which controls the locking mechanism has made one-half of one revolution. This, as already explained, will result, assuming that at the beginning of the 25 operation the plows were locked out of the ground as indicated in Fig. 3, in releasing the lock and permitting the plows to successively drop into the ground in working position. When the operator desires to take 30 them out of the ground, he can pull upon the rope as before and release the rope as soon as the mechanism is started. At this moment the parts are in the position indicated in Fig. 5 and the shaft A⁶ will be 35 rotating the rollers and the gear wheel C¹ will complete its complete rotation or perform the second half thereof. This, as previously explained, retracts the plow rods, 40 raises the plows out of the ground, and finally causes the lock to engage and to operate to lock the plows in position out of the ground.

It will be noted that I have selected arbitrarily 17 and 34 for the teeth C and C¹, 45 thus giving C¹ twice as many teeth as C. It will be quite obvious that any other suitable number might have been used.

I claim:

1. A plow lift mechanism comprising a 50 movable part, a plow rod connected thereto, a spring actuated lock on the movable part, means for moving the movable part to lift or lower the plows and means to successively

apply tension or pressure to the spring to cause it to engage or free the lock. 55

2. A plow lift mechanism comprising a swinging part, a plow rod connected thereto, a lock on the movable part, a spring to actuate it, means for moving the movable part to lift or lower the plows and means to successively apply tension or pressure to the 60 spring to cause it to engage or free the lock.

3. A plow lift mechanism comprising a depending swinging part, a plow rod connected to the lower end thereof, a lock on the 65 movable part, a spring to actuate it, means for moving the part to lift or lower the plows and means to successively apply tension or pressure to the spring to cause it to engage or free the lock. 70

4. A plow lift mechanism comprising a depending swinging part, a plow rod connected thereto, a lock on the movable part containing a pivoted portion, a spring to actuate it, means for moving the movable 75 part to lift or lower the plows and means to successively apply tension or pressure to the spring to cause it to swing the pivoted part and thus to engage or free the lock.

5. A plow lift mechanism comprising a 80 pivoted link, a plow rod connected with the lower end thereof, a pivoted lock lever on the end of the link, a spring connected with the free end of such lever, means for swinging the link to lift or lower the plows and 85 means to successively apply tension or pressure to the spring to cause it to rock the lock lever on its pivot.

6. A plow lift mechanism comprising a 90 series of pivoted links, a series of plow rods connected one to the lower end of each such link, a pivoted lock lever on the end of the link, a spring connected with the free end of such lever, means to successively apply tension or pressure to all the springs to cause 95 them to tend to rock the lock lever on its pivot and means for successively swinging the links to lift or lower the plows in succession.

In testimony whereof, I affix my signature in the presence of two witnesses this 25th day of November, 1913.

WILLIAM H. C. HIGGINS, JR.
